MOTOR-CONTROLLING APPARATUS.

1,102,491.

Specification of Letters Patent.

Patented July 7, 1914.

Application filed November 21, 1906. Serial No. 344,490.

To all whom it may concern:

Be it known that I, ERNEST L. GALE, Sr., a citizen of the United States, residing at Yonkers, in the county of Westchester and 5 State of New York, have invented a new and useful Improvement in Motor-Controlling Apparatus, of which the following is a specification.

My invention relates to apparatus for 10 controlling electric currents, and more particularly those used for starting and controlling electric motors.

One of the objects of my invention is the provision of simple and efficient means for 15 automatically controlling electric motors with minimum consumption of current.

A further object of my invention is the provision of a reversing switch of the gravity type in an automatic current controlling 20 system.

Another object of the present invention is the provision of an electro-magnetic reversing switch for an electric motor and means for reducing the current for operating said 25 switch to substantially zero after the motor has attained a predetermined speed.

Other objects of the invention will appear hereinafter, the novel combinations of 30 elements being pointed out in the claims.

30 In the accompanying diagram of circuits and connections there is illustrated one form of my invention.

1 designates a motor armature, a shunt field coil being designated by the reference 35 number 9. Although a rotary motor is here shown which is adapted to be controlled by the apparatus hereinafter described, I wish it to be understood that such a motor is here shown only by way of illustration, and that 40 other electric devices desired to be controlled may be substituted therefor; such for example, as a series alternating current motor of the commutator type, a reciprocating motor, or an electro-magnetic device, 45 etc.

4^A designates an opposition element which is here shown diagrammatically as an ohmic resistance, but which may be resistance and inductance or inductance alone, or capacity, 50 etc., depending upon the nature of the current used. This opposition element is usually proportioned in the well known way to prevent excessive current from passing through the motor upon starting the same.

55 + and - designate mains which are con-

nected directly to the reversing switch R and the manual controlling switch 42, respectively. The shunt field 9 is connected between the positive main at the point 56 and the circuit 17 at the point 57. 60

The reversing switch R comprises in this instance fixed insulating supports 53 and 53' on which are mounted spring-pressed contacts 28, 29, and 28', 29', respectively.

Adapted to engage with these contacts are 65 the contacts 23, 24 which are insulated from each other and mounted on the switch lever 22 which is pivoted at 23.

A downwardly extending arm of the lever 22 has a pin-and-slot connection 39 with the stem 18 70

which rigidly connects the cores 40, 40' of the reversing switch magnet-solenoids 41, 41', respectively. It will be seen that the switch lever 22 is so arranged with regard to the 75

spring-pressed contacts that it will be held by gravity in either of its stationary positions, and that the position of said lever can be changed from one side to the other by the reversing switch magnets.

Connected to the wire 10 at the point 61 80 is a wire 11 which leads to the solenoid 2^A. A wire 12 connects the other terminal of the solenoid 2^A to the fixed contact strips 44

and 44' of the manually operated switch 42. When the switch lever 43 is moved onto 85

either of these contact strips, a circuit is completed from the positive to the negative main through the motor armature and solenoid 2^A to excite the latter and cause the same to lift its core 8 and thereby insert 90 the opposition element 4^A in circuit with the motor armature 1, said opposition element being normally short-circuited by the wires 10, 16 and 17, contacts 5 and 6, and the bridge piece 7. The bridge piece 7 is connected to the core 8, and therefore when the latter is lifted, the contacts 5 and 6 are electrically disconnected. 95

The circuit through the solenoid 2^A may be traced from the positive main through the 100 wire 2 to the contacts 29' and 24, and thence by way of wire 13 to and through motor armature 1, wire 14, contacts 25 and 28', wires 15, 10, 11, solenoid 2^A, wire 12, contact strip 44 or 44', and switch lever 43 to 105 the negative main. While the short circuit around the opposition element 4^A is still closed, the small current which passes through the circuit just traced will not be sufficient to operate the motor nor to injure 110

the same by excessive current, by reason of the resistance of the solenoid 2^A. The operation of inserting the starting resistance is done so quickly, however, that the motor 5 starts immediately after the manual switch is closed. Furthermore, it will be noticed that a shunt circuit is completed from the point 51 through resistance 46, wire 52', contacts 4, 3, and bridge piece 7^E, and wire 10 52 to the point 50, around the motor armature 1, thus shunting away part of the current from the latter. Although the resistance 4^A is inserted in series with the motor armature 1 by the lifting of the core 15 8 and bridge piece 7, the motor circuit indicated by the heavy lines is still open at the contacts 5^E, 6^E, and the bridge piece 7^E is not lifted at this time so the circuit through the solenoid 2^E is still open at the 20 manual switch 42.

When the switch lever 43 is moved in either direction it first engages contact strip 25 45 or 45' to complete a circuit from the point 50 through one of the reversing switch magnet solenoids 41 or 41' by way of wires 47 or 47'. The lever 43 next engages the contact strip 44 or 44' to effect the excitation of the solenoid 2^A. When said lever is moved to one of its extreme positions it engages also the contact 26 or 26' and thus closes a circuit through the solenoid 2^E by way of wire 55, wire 27, contact 26 or 26', lever 43 and wire 54 to the — main. The bridge piece 7^E will thereupon be lifted to 30 35 electrically connect the contacts 5^E and 6^E and thus close the motor circuit; the solenoid 2^E, core 8^E, contacts 5^E, 6^E, and bridge piece 7^E comprise an electro-magnetic switch in this instance.

40 The operation of the system may be understood from the following explanation: Let it be assumed that the switch lever 43 is moved to the left so as to engage the contact 45. At this time the motor circuit is 45 open at the main line switch comprising the contacts 5^E and 6^E, but a circuit may be traced from the + main through the contacts 29', 24, wire 13, armature 1, wire 14, contacts 25, 28', wires 15, 58, solenoid 41', wire 47, contact strip 45, lever 43, to the — main. At the same time a parallel circuit through the solenoid 41' is closed by way of wire 2, resistance 46, wire 52', contacts 4 and 3, bridge piece 7^E, wires 52 and 58, solenoid 41', wire 47, contact strip 45, and lever 43 to the — main. The core 40' will therefore be drawn to the right and the lever 22 and parts connected therewith will be thrown to their left-hand position where 50 55 60 65 they will be held by gravity assisted by the pull on the switch solenoid 41'. It will therefore be noticed that when the contacts 24, 25 leave the contacts 29', 28', respectively, the solenoid 41' still receives current, and the lever 22 is acted upon by the sole-

noid 41' from its initial position to its final position. In other words, one of the parallel circuits through the solenoid 41', namely, the circuit including the switch contacts 25 and 28', will be opened while the switch lever 22 is in the act of being thrown from one side to the other; the parallel circuit by way of the resistance 46 through the solenoid 41', as before pointed out, is maintained, however. Now if the lever 43 is moved to its right-hand position 70 75 80 85 it will engage the contact strip 45' to effect the excitation of the solenoid 41 to move the lever 22 back to its right-hand position. In this case as soon as the contacts 25, 24, leave the contacts 28, 29, respectively, one of the parallel circuits including the solenoid 41 is opened, but the other parallel circuit is maintained as before and the lever 22 is thrown over to effect a reversal of the motor connections. If desired, the contacts 24, 25 may be spring-pressed and those designated 28, 29, 28', 29' fixed. Upon further movement of the lever 43 to the left, the contact strip 44 is also engaged, whereupon a shunt circuit will be completed from a point 61 through the wire 11, solenoid 2^A, wire 12, contact strip 44, lever 43 to the — main. The bridge piece 7 will then be lifted and the resistance 4^A inserted in series with the motor armature 1. When the lever 43 is moved to its extreme left-hand position a circuit is completed from the + main through wire 55, solenoid 2^E, wire 27, to the — main. The energization of the main line switch magnet will cause the bridge piece 7^E to be lifted upwardly to connect the contacts 5^E and 6^E. The lever 22 being in its left-hand position, the motor circuit may be traced from the + main through wires 2', contacts 28, 25, wire 14, armature 1, wire 13, contacts 24, 29, wires 15', 15, resistance 4^A, wire 17, contact 5^E, plate 7^E, contact 6^E, wire 54, to the — main. If the lever 43 were moved to its extreme right-hand position, the lever 22 would be thrown to its right-hand position and the motor-armature circuit thus traced will be altered in a well known manner to effect a reversal of rotation of said armature. 90 95 100 105 110 115 120 125 130

It should be noted that the solenoid 2^E and shunt field 9 are connected directly across the mains, whereas the solenoid 2^A and the solenoids 41, 41' are connected across the opposition element 4^A. Upon the closing of the automatic main line switch by means of the solenoid 2^E, the motor will start at slow speed and a potential will be maintained across the opposition element 4^A to keep the solenoid 2^A sufficiently energized to hold the bridge piece 7 in its uppermost position. As the armature attains a predetermined speed the potential across the opposition element 4^A will decrease gradually until the current passing through

the solenoid 2^A will no longer be sufficient to hold the bridge piece 7 in its lifted position. The short-circuit around said opposition element will therefore be automatically closed. This will also have the effect of short-circuiting the solenoids 2^A and 41 or 41', thus substantially eliminating the current therein.

So long as the switch lever 43 is held in one of its extreme positions the motor will continue to run at full speed. When it is desired to stop the motor the lever 43 is moved out of engagement with the contact 26, whereupon the bridge piece 7^E will drop to electrically connect the contacts 3 and 4 and thus close a local circuit including the armature 1 and resistance 46. This local circuit is an electro-dynamic brake circuit and may be traced from the armature 1 through wire 13, contacts 24 and 29', resistance 46, wire 52', contacts 3, 4 and bridge piece 7^E, wires 52, 15, contacts 28', 25, and wire 14 back to the motor-armature 1. The motor is now running as a generator, being driven by the momentum of the moving parts or by the load on the motor which may be a descending elevator car connected through hoisting mechanism to said motor.

In order to again start the motor, the switch-lever 43 may be brought into engagement with the contact 26 or 26' which will have the effect of closing the automatic main line switch, thus opening the electro-dynamic brake circuit and closing the main line circuit through the motor armature, so that the current may again drive the motor and cause the same to do work. When the motor is stopped in the manner explained, the solenoid 2^A remains deenergized, but upon again starting the motor, the resistance 4^A will be inserted in series with the motor armature and then automatically short-circuited to bring the motor up to full speed. It will therefore be seen that in order to stop the motor the switch 43 should be brought back to central position, when the electro-dynamic brake circuit will be closed to gradually slow down the motor and if desired, any well known brake-ap₁ means may be held in released position by an electro-magnet connected across the mains, while the motor is operated, said electro-magnet being disconnected from the mains when the lever 43 is brought to central position.

Obviously those skilled in the art may make various changes in the details and arrangement of parts of my invention without departing from the spirit and scope thereof, and I desire therefore not to be limited to the precise construction herein disclosed.

Having thus described my invention, what I claim and desire to have protected by Letters Patent of the United States is:—

65 1. In current-controlling apparatus, the

combination with a motor, of a reversing switch therefor, an electro-magnet initially in circuit with the armature of said motor for operating said switch, and means for substantially eliminating the current in said electro-magnet upon the motor attaining a predetermined speed. 70

2. In current-controlling apparatus, the combination with a motor, of a reversing switch of the gravity type comprising a lever, two electro-magnets for actuating said switch, means for initially placing one of said magnets in circuit with the motor armature to effect the energization of said magnet and the actuation of the switch lever to final position and hold the same in such position, and means for substantially eliminating the current in said magnet to permit gravity alone to hold said switch lever in final position. 75

3. In motor-controlling apparatus, the combination with a motor, of an opposition element, a reversing switch of the gravity type for said motor, two electro-magnets for operating said reversing switch to either of its stationary positions, a controlling electro-magnet, a manual switch for connecting one of said reversing switch magnets and said controlling magnet across the opposition element, and a switch operated by said controlling magnet to initially insert said opposition element in circuit with the motor and thereafter short-circuit said opposition element and substantially eliminate the current in the reversing switch magnet and in 100 said controlling magnet. 95

4. In motor-controlling apparatus, the combination with a motor, of starting resistance, an additional resistance in parallel with the motor-armature, means for initially inserting said starting resistance in series with the motor-armature, and thereafter automatically cutting out said resistance upon the motor attaining a predetermined speed, and means for cutting out said additional resistance and closing the main line circuit. 105

5. In motor-controlling apparatus, the combination with a motor, of starting resistance therefor, a reversing switch of the gravity type, electro-magnets for operating said reversing switch, and a circuit in parallel to the motor-armature to maintain either of said magnets energized while the switch is being moved from one position to another. 115

6. In motor-controlling apparatus, the combination with a motor, a reversing switch comprising a member having two positions, electro-magnets for operating said reversing switch, and a circuit in parallel to the motor-armature to maintain one of said magnets energized while said member is being moved from one position to another. 125

7. In motor-controlling apparatus, the combination with a motor, of a normally 130

- closed resistance circuit in parallel to the motor-armature, a reversing switch, electro-magnets connected to receive current through said resistance circuit and controlled thereby for operating said reversing switch, and means for opening said resistance circuit and closing the main line circuit.
8. In motor-controlling apparatus, the combination with a motor, of reversing switches therefor, starting resistance, means for initially inserting said resistance in series with the motor-armature, and for cutting out the same when the motor attains a predetermined speed, an automatic main line switch, an electro-dynamic brake circuit, means co-acting with said switch for controlling said brake circuit, and a manual switch for controlling said automatic main line switch and the controlling means co-acting therewith.
9. In motor-controlling apparatus, the combination with a motor, of an electro-dynamic brake circuit for said motor, a reversing switch, electro-magnets for operating said reversing switch, and circuits and connections co-acting with a part of said electro-dynamic brake circuit for maintaining either of the reversing switch magnets energized while the reversing switch is being moved from one position to another.
10. In motor-controlling apparatus, the combination with a motor, of reversing switch apparatus therefor, two electro-magnets for operating said reversing switch, and means for maintaining either of said switch magnets energized until the motor attains a predetermined speed and then substantially eliminating the current therein.
11. In motor-controlling apparatus, the combination with a motor, of a reversing switch comprising a single member having two positions, two electro-magnets for actuating said member, conductors affording a path for current through one of said electro-magnets while the same is actuating the reversing switch member from one position to another, and means for controlling the connection between said conductors.
12. In motor-controlling apparatus, the combination with a reversing switch comprising a single arm having two positions, two electro-magnets one for actuating said arm in one direction and the other for actuating said arm in the other direction, means for maintaining one of said electro-magnets energized while it is actuating said arm from one position to the other, and means for substantially eliminating the current in said actuating electro-magnet after the reversing switch has been operated.
13. In motor-controlling apparatus, the combination with a reversing switch of the gravity type, of electro-magnets for operating said switch, a manual switch for effecting the energization of either of the said electro-magnets to throw the switch from one position to the other, an electro-magnetic main line switch controlled by said manual switch, an auxiliary switch co-acting with said electro-magnetic main line switch, said auxiliary switch being closed when said main line switch is open, and a circuit controlled by said auxiliary switch to maintain either of said electro-magnets energized while the reversing switch is being thrown.
14. In motor-controlling apparatus, the combination with an electric motor, of reversing switch mechanism therefor, electro-magnets for operating said reversing switch, a starting resistance, a switch normally short-circuiting said starting resistance, an electro-magnet for operating said switch, a main line switch, an additional resistance normally connected in parallel to the armature, an auxiliary switch for controlling said additional resistance, an electro-magnet for controlling said main line switch and said auxiliary switch, and a single device for controlling all of the aforesaid electro-magnets.
15. In motor-controlling apparatus, the combination with an electric motor, of a reversing switch therefor, electro-magnetic mechanism for operating said reversing switch, starting resistance, an electro-magnetic switch for initially inserting said starting resistance and thereafter cutting out the same upon the motor attaining a predetermined speed, an electro-magnetic main line switch, means for maintaining a supply of current to said electro-magnetic mechanism, to said electro-magnetic switch for the insertion of the starting resistance, and to the electro-magnetic main line switch, and to effect the substantial elimination of current in said electro-magnetic mechanism and in the electro-magnet for operating the starting resistance switch, after the motor has attained a predetermined speed.
16. The combination with an electric motor, of starting resistance therefor, means for inserting said resistance, a main line switch, and a circuit controlling device arranged first to energize and effect the operation of the resistance inserting means and thereafter energize and effect the operation of the main line switch, whereupon the said resistance inserting means is automatically restored to original position to cut out said resistance.
17. In motor-controlling apparatus, the combination with a motor, of starting resistance, a reversing switch for the motor, electro-magnetic mechanism for operating said switch, an accelerating switch, an electro-magnet for controlling said accelerating switch in accordance with the speed of the motor, and circuits and connections for effecting the supply of current to said electro-

magnetic mechanism and said accelerating switch controlling electro-magnet for a brief period of time only.

18. In motor-controlling apparatus, the combination with a direct current motor, of starting resistance in circuit therewith, a reversing switch for controlling said motor, an electro-magnet for operating said switch, and means for eliminating substantially all the current in said electro-magnet when said starting resistance is cut out.

19. In motor-controlling apparatus, the combination with a direct current motor, of starting resistance in circuit therewith, a reversing switch for the motor, electro-magnetic mechanism for operating said switch, means for controlling said starting resistance, and circuits and connections for effecting the substantial elimination of current

from all circuits except those of the motor 20 itself upon the motor attaining a predetermined speed.

20. In motor-controlling apparatus, the combination with a motor, of starting resistance therefor, a reversing switch of the 25 gravity type, electro-magnets for operating said reversing switch, and a circuit to maintain either of said magnets energized while the switch is being moved from one position to another.

In testimony whereof, I have signed my name to this specification in the presence of two subscribing witnesses.
